(57) **CLAIM**

The ornamental design for a horizontal scissor tip compaction cleat, as shown and described.

DESCRIPTION

FIG. 1 is a perspective view of a horizontal scissor tip cleat in accordance with an embodiment of the present invention.

FIG. 2 is a side elevational view of the horizontal scissor tip cleat of FIG. 1.

FIG. 3 is an end elevational view of the horizontal scissor tip cleat of FIG. 1.

FIG. 4 is a top plan view of the horizontal scissor tip cleat of FIG. 1; and,

FIG. 5 is a bottom plan view of the horizontal scissor tip cleat of FIG. 1.

The broken lines shown in all figures are for illustrative purposes only and form no part of the claimed design.
